(57) **CLAIM**

The ornamental design for a cabinet lock as shown and described.

DESCRIPTION

The patent or application file contains at least one drawing executed in color. Copies of this patent or patent application publication with color drawing(s) will be provided by the Office upon request and payment of the necessary fee.

1. Cabinet lock
2. Cabinet lock
3. Cabinet lock
4. Cabinet lock
- 1.1 : Front, top, right side perspective view
- 1.2 : Right side elevational view
- 1.3 : Left side elevational view
- 1.4 : Top plan view
- 1.5 : Bottom plan view
- 1.6 : Front elevational view
- 1.7 : Rear elevational view
- 2.1 : Front, top, right side perspective view
- 2.2 : Right side elevational view
- 2.3 : Left side elevational view
- 2.4 : Top plan view
- 2.5 : Bottom plan view
- 2.6 : Front elevational view
- 2.7 : Rear elevational view
- 3.1 : Front, top, right side elevational view
- 3.2 : Right side elevational view
- 3.3 : Left side elevational view
- 3.4 : Top plan view
- 3.5 : Bottom plan view
- 3.6 : Front elevational view
- 3.7 : Rear elevational view
- 4.1 : Front, top, right side elevational view
- 4.2 : Right side elevational view
- 4.3 : Left side elevational view
- 4.4 : Top plan view
- 4.5 : Bottom plan view
- 4.6 : Front elevational view
- 4.7 : Rear elevational view

The broken lines in the figures illustrate portions of the cabinet lock that form no part of the claimed design.

1 Claim, 28 Drawing Sheets
(18 of 28 Drawing Sheet(s) Filed in Color)
